UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y.

TELEPHONE-EXCHANGE SYSTEM.

Application filed April 24, 1919. Serial No. 292,254.

To all whom it may concern:

Be it known that I, SAMUEL B. WILLIAMS, Jr., a citizen of the United States, residing at Brooklyn, in the county of Kings, State 5 of New York, have invented certain new and useful Improvements in Telephone-Exchange Systems, of which the following is a full, clear, concise, and exact description.

10 This invention relates to improvements in telephone exchange systems and has particular reference to a switching arrangement therefor.

An object of the invention is to provide 15 an improved interconnecting means for telephone lines which will have the advantage of certain so-called relay systems and, at the same time, may be operated in the manner of and in accordance with the present 20 day full automatic practice.

Heretofore such relay systems have either required the extension of large numbers of conductors to each subscriber's line or have required such systems to be operated in a 25 peculiar manner or in a manner different from the present day standard automatic practice.

Another object of the invention is to so arrange the circuits that the system may 30 cooperate with present day standard telephone systems and involve no new methods of operating therein.

A further object is to produce a novel impulse controlling mechanism for controlling 35 the subscriber's line interconnecting means which may be actuated through the operations ordinarily performed at an automatic telephone substation.

A still further object is to reduce to a minimum 40 the necessary interconnecting apparatus and to thereby simplify, cheapen and make more efficient such a system.

An additional object is to reduce the amount of apparatus necessary by making 45 as much of it as possible common to all subscribers and to provide only as much of such common apparatus as traffic conditions will allow.

In carrying out the above objects, the various 50 connections made in establishing a call between two subscribers' lines or between a subscriber's line and a central office trunk are preferably controlled by relays. The control of the relays is responsive to the 55 variable operations of a common set of

counting relays actuated by the substation senders. With the counting relays, and for the purpose of reducing the number of pieces of apparatus used, a translating device is employed which translates the decimally set up condition of the counting relays to a non-decimally set up condition at a set of code relays, which in turn retranslate said non-decimally set up condition into a decimally set up condition for actuating the 60 subscriber's line interconnecting means.

The inventive idea involved is capable of receiving a variety of expressions one of which, for the purpose of illustrating the invention, is shown in the accompanying 65 drawings, but it is to be expressly understood that said drawings are employed only for the purpose of facilitating the description of the invention as a whole and not to define the limits thereof, reference being had 70 to the appended claims for this purpose.

In the drawings Figs. 1, 2, 3 and 5 with Fig. 2 arranged beneath Fig. 1, Fig. 3 to the left of Fig. 2, and Fig. 5 beneath Fig. 3, illustrate diagrammatically the circuits employed in carrying out the invention. Fig. 4 is a tabulation of an impulse translating 75 code used in connection with the impulse controlling mechanism.

Briefly, the invention is shown as used in 80 connection with a private branch exchange system. The subscribers' lines within the exchange are arranged to have access to any one of a plurality of outgoing link circuits, the number of such circuits being less than 85 the number of the subscribers' lines.

Two outgoing link circuits are shown in Fig. 2, although it will be understood that as many circuits may be employed as is found necessary to adequately handle the particular traffic conditions encountered. Each outgoing link circuit has permanently paired or associated therewith an incoming link circuit for completing a loop circuit from a calling to a called subscriber's line. Upon 90 the automatic selection of any one of the outgoing link circuits, when a call is initiated, the subscriber's line is extended, by the energization of a relay at the point of junction of said line with said outgoing link 95 circuit, to a mechanism shown at the right of Fig. 3 which is individual to the outgoing and incoming link circuits selected. An idle impulse controlling mechanism shown in Fig. 5 and common to a plurality 100 of

110

of link circuits is then selected through junction relays shown at the left of said figure. In response to sets of impulses transmitted from the calling subscriber's substation, certain counting relays of said controlling mechanism are operated in accordance with a suitable code shown in Fig. 4. Through the operation of a particular counting relay actuated, when the first set 10 of impulses is transmitted, a certain translating relay or relays, illustrated at the left of Fig. 3, are energized to select one of a group of relays corresponding to the first digit of the called line. Enclosed by the 15 dotted lines at the left of Fig. 3 are a plurality of groups of switching devices or relays individual to the seized link circuits, the relays of each group being individual to a subscriber's line. The selection of any 20 one of the group of relays corresponding to the first digit of the called line determines in which of the groups the particular relay individual to the wanted line is located. The last set of impulses transmitted 25 through the impulse controlling mechanism then determines the relay in the selected group which is individual to the wanted line, whereupon the desired connection is established.

30 Provision is also made for establishing a connection from a subscriber's substation within the exchange to a trunk leading to a central office exchange. In this instance, an outgoing link circuit is seized by the calling 35 subscriber in the same manner as previously referred to, with a result that the apparatus individual to said link circuit and an impulse controlling mechanism common to a number of link circuits, are also engaged for 40 use. Only one set of impulses is required to establish a connection to a central office trunk, and the transmission of this set of impulses will operate one of the counting 45 relays of the controlling mechanism to establish a certain electrical condition. This 50 electrical condition is conveyed to the group of translating devices or relays which again coordinate to actuate another relay common to the central office trunks. In response to the actuation of this latter relay, an idle 55 central office trunk is seized and the next idle trunk simultaneously pre-selected to handle another call.

55 In establishing a call from a central office exchange to a subscriber within the private branch exchange, a connection is first set up automatically from the central office operator's position to one of a plurality of receiving stations in the private branch exchange which is automatically pre-selected. 60 These receiving stations are of the same nature as a subscriber's substation and upon the selection of one of them, the attendant thereat, in response to information conveyed 65 by the central office operator, may dial for

the wanted subscriber in the same manner as referred to in connection with the establishment of a call between subscribers within the exchange.

70 It is believed that the invention will now be fully understood from the following detailed description of the operation in establishing the various connections. Let it first be assumed that a subscriber at substation A desires to establish a connection with another subscriber within the private branch exchange. Upon removal of the receiver from its switchhook at substation A, a circuit is closed for relay 100 extending from 75 grounded battery, winding of said relay, back contact and outer armature of cutoff relay 101, substation apparatus, inner armature and back contact of relay 101 to ground. Relay 100 energizes and closes a circuit at its left-hand armature for relay 80 102 extending from grounded battery, winding of relay 102, front contact and left armature of relay 100 to ground. Assuming that the first outgoing link circuit is idle, 85 energization of relay 100 closes a circuit extending from ground, right armature and contact of relay 100, right armature and back contact of relay 302 individual to said link circuit and winding of relay 200 to grounded 90 battery. The ground from the right-hand contact of relay 100 is also extended through the right-hand contact of relays 302 of all other link circuits to energize relays similar to relay 200, but the energization of these other relays 200 has no effect as will presently appear. Relay 200 of the link circuit 95 above mentioned becomes energized and closes a circuit for junction relay 201, extending from grounded battery, outermost armature and front contact of relay 102, 100 winding of relay 201, front contact and middle armature of relay 200 to ground. In the same manner, junction relays similar 105 to relay 201, such as relay 203, will also energize if their associated relays 200 are operated. Relay 201 of the first idle link energizes in the above circuit and closes a circuit 110 for line relay 300 extending from grounded battery, right winding of relay 300, back contact and inner left armature of relay 301, 115 middle left armature and front contact of relay 201, substation apparatus A, front contact and outer left armature of relay 201, outer left armature and back contact of relay 301, and left winding of relay 300 to ground. 120 Energization of relay 300 closes a circuit for slow-to-release relay 303 extending from grounded battery, winding of said relay, front contact and armature of relay 300 to ground. Upon attracting its right armature, relay 303 closes a locking circuit for junction relay 201, extending from grounded battery, winding of cutoff relay 101, inner 125 left armature and front contact of relay 201, winding of said relay, front contact and 130

right armature of relay 201, the back contacts and right armatures of all other junction relays associated with the outgoing circuit employed including the last relay 202, 5 winding of relay 302, right armature and front contact of relay 303 to ground. It will here be apparent that by the opening of the inner left-hand armature and back contact of relay 201, when this relay operated, 10 the locking circuits for relays 203 and other similar relays will be permanently opened so that these relays cannot lock up after being energized. Relay 101 is energized in this circuit and at its inner armature re- 15 moves the holding ground for relay 100 which deenergizes and in turn causes the de-energization of relay 102. Relay 302 is also energized in the circuit just described, and at its right armature breaks the circuit for 20 relay 200 which then releases. By the re-lease of relay 100 and removal of ground from its right-hand contact, other relays similar to relay 200 which might have been energized, will be caused to release and re- 25 move ground from the windings of relays 203 and other like relays, so that these relays will then release. Thus, it will be seen that although several junction relays may be energized when a call is initiated, only the re- 30 lay associated with the first idle link circuit encountered will remain energized and the others will restore. When relay 302 energizes, a circuit is established for relay 304 extending from grounded battery, winding 35 of said relay, back contact of inner armature of relay 305, back contact and middle left armature of relay 306, front contact and left armature of relay 302, back contact and upper armature of relay 316 to ground. En- 40 ergization of relay 304 causes the selection of an idle impulse controlling mechanism, a number of which mechanisms are provided for the purpose of handling simultaneous calls. Assuming that the controlling mecha- 45 nism shown in Fig. 5 is the first idle one, en- ergization of relay 304 establishes a circuit extending from grounded battery, winding of relay 500, upper armature and back contact of relay 503, front contact and 50 left armature of relay 304 to ground. Re-lays 500 of other idle mechanisms will also energize, but their operations have no effect as will presently be pointed out. Relay 500 of the first idle mechanism energizes and 55 closes a circuit traceable from grounded battery, inner right armature and front contact of relay 304, winding of junction relay 501, winding of junction relay 501' in series with relay 501, front contact and middle 60 lower armature of relay 500 to ground. Re-lays 501 and 501' energize and lock up over a circuit extending from grounded battery, outer right armature and back contact of relay 301, outer armature and back contact 65 of relay 307, outermost left armature and back contact of relay 306, winding of relay 305, right armature, front contact and winding of relay 501, winding, front contact and left armature of relay 501', back contact and left armature of relay 502, and winding of 70 relay 503 to ground. Relays 305 and 503 are both energized in this circuit and at its outer armature, relay 305 connects the dial tone apparatus DT to the subscriber's line over the circuit extending from ground 75 through dial tone apparatus, back contact and outer right armature of relay 310, front contact and outer armature of relay 305, back contact and innermost left armature of relay 306, and right winding of relay 309 to grounded battery. Relay 309 does not, however, energize but the dial tone is induced into the left winding thereof and then traverses the previously described circuit for relay 300 through the calling sub- 80 scriber's substation apparatus. This dial tone is furnished to the calling subscriber to indicate that the impulse controlling mechanism of Fig. 5 has been selected and ready to receive impulses transmitted from 85 the calling substation. Operation of relay 305 breaks the circuit for relay 304 which then releases. Relay 503, in attracting its upper armature, opens the circuit for relay 500 which also releases. Returning now to 90 the point in the operation where relay 304 is energized to establish a circuit for relay 500, if there are other impulse mechanisms idle at this time, relays 500 of such mechanism will also be operated and the junction 95 relays similar to relays 501 and 501' will be energized in the same manner as described for the latter relays. However, these other similar relays cannot lock up for the reason that their locking circuits extend through 100 the right armature and back contact of relay 501 which is at this time operated. Relays 503 of mechanisms other than the first idle one will therefore not operate as the circuits for these relays must also pass through 105 the right armature and back contact of relay 501. It therefore follows that when relay 304 is released as above described, the relays 500 of the other idle impulse mechanisms will deenergize and cause the release 110 of junction relays similar to relays 501 and 501'. The subscriber at substation A may now 115 manipulate his impulse sending device 103 in accordance with the first digit of the 120 wanted line, and in response to the impulses transmitted, armature of line relay 300 will vibrate, but relay 303 being slow to release will remain energized during the transmission of the set of impulses. Upon the first 125 deenergization of relay 300, a circuit is closed for slow-to-release relay 504 extending from grounded battery, winding of said relay, winding of relay 505, front contact and inner left armature of relay 501, front con- 130

tact and left armature of relay 303, back contact and armature of relay 300 to ground. Relays 504 and 505 are energized in this circuit and at its left armature, relay 504 closes 5 a circuit for slow-to-release relay 506 extending from grounded battery, winding of relay 506, front contact and left armature of relay 504 to ground. Relay 506 locks up over a circuit extending from grounded bat- 10 tery, winding, right armature and front contact of relay 506, back contact and armature of relay 507, back contact and left armature of relay 508 to ground. Energization of relay 504 also closes a circuit for relay 15 509 extending from grounded battery, winding of relay 509, back contact and left armature of relay 510, right armature and front contact of relay 504, front contact and lower armature of relay 503 to ground, said relay 20 503 having become energized in the previously described locking circuit for relays 501 and 501'. Relay 509 locks up over a circuit extending from grounded battery, winding, armature and front contact of said relay, 25 winding of relay 510, front contact and lower armature of relay 503 to ground. Relay 510 does not, however, energize in this circuit at this time, due to a shunt circuit which extends from ground at the lower 30 armature and front contact of relay 503, front contact and right armature of relay 504, left armature and back contact of relay 510, armature and front contact of relay 509, and winding of relay 510 back to ground 35 at the lower armature and front contact of relay 503. Energization of pulsing relay 505 in response to the first impulse transmitted establishes a circuit for counting relay 1 extending from ground, front contact 40 and armature of relay 505, the right armatures and back contacts of relays 1' to 10' and winding of counting relay 1 to grounded battery. This counting relay energizes and locks up over a circuit extending from 45 grounded battery, winding of said relay, front contact and right armature thereof, winding of relay 1', back contact and left armature of relay 2', front contact and left armature of relay 506 to ground. Relay 1', 50 however, does not become energized in this circuit due to a shunt extending from ground at the armature of relay 505, through the back contacts and right armatures of relays 1' to 10', front contact and armature 55 of relay 1, winding of relay 1' to ground at the front contact and left armature of relay 506. Upon the release of relay 505 at the termination of the first impulse, this shunt is removed and relay 1' then energizes, and 60 at its right armature prepares a circuit for relay 2 which energizes when relay 505 is operated in response to the second impulse. This energizing circuit for counting relay 2 would then extend through the front contact and 65 right armature of relay 1', and upon energi-

zation of said counting relay the same would lock up through the winding of relay 2' to the locking ground at the front contact and left armature of relay 506. The same action takes place with relay 2' as that described for relay 1', and upon energization of relay 2' its left armature breaks the locking circuit for counting relay 1 which extends through the winding of relay 1' and said counting relays 1 and 1' would therefore deenergize. This 70 operation continues until the impulses corresponding to the first digit of the wanted line have been transmitted and the last counting relay to become energized remains locked up while all of the preceding counting relays deenergize. 75

In order to reduce to a minimum the number of relays employed in selecting the desired line, the impulse controlling mechanism includes a translation system, the code 80 for which is illustrated in Fig. 4. In explanation of this code it is pointed out that there are four conductors, 511, 512, 513 and 514 associated with the counting relays, said conductors being denoted at the top of Fig. 85 4 as 1, 2, 3 and 4 respectively. Ten impulses are numbered at the left of said figure, and it will be seen that one impulse will apply ground, designated by 0, to the first conductor 511. Two impulses will apply ground 90 to conductors 512, four impulses to conductors 511 and 512, and so on in different combinations, ten impulses being adapted to connect ground to the three conductors 511, 512 and 514. 95

At the termination of the first set of impulses corresponding to the first or tens digit of the wanted line, relay 300 remains energized and causes the release of relay 505. At the expiration of a short period of time, 100 slow-to-release relay 504 also releases, and at its right armature immediately opens the previously described shunt circuit for relay 510 which then energizes in the locking circuit for relay 509, which circuit finds ground 105 at the lower armature and front contact of relay 503. Energization of relay 510 closes a circuit from grounded battery, winding of marginal transfer relay 310, back contact and left armature of relay 308, outer left 110 armature and front contact of relay 501, right armature and front contact of relay 510, left armature and back contact of relay 515, winding of relay 507, front contact and left armature of relay 506 to ground. Relay 507 energizes and breaks the locking circuit 115 for slow-to-release relay 506 which, after an interval of time, releases. Relay 310, being marginal, does not energize in series with relay 507. Energization of relay 507 establishes a circuit for relay 516 traceable from 120 grounded battery, winding of relay 516, front contact and armature of relay 507, back contact and left armature of relay 508 to ground. Relay 516 energizes and by at 125 130

tracting its armatures extends the conductors 511, 512, 513 and 514 to the junction relay 501'. It will be seen by reference to the translating mechanism shown at the left of Fig. 3 that the relays, including relay 317, which are individual to the subscriber's lines, are controlled by two sets of conductors, one extending through the back and the other through the front contacts of relay 310. The selection of a group of these individual relays is controlled through the back contacts of said relay by the energization of one of the translating relays, while the selection of an individual relay in the selected group is controlled through the front contact of said relay 310. It is thus obvious that any one of the individual relays may be identified by electrically distinguishing two conductors, one each in the principal direction of a two co-ordinate system. For the purpose of illustration, let it be assumed that the tens digit of the wanted line is 1. In this case, counting relay 1 is the only relay energized and locked up and a circuit will then be established from ground at the left armature and front contact thereof, conductor 511, uppermost armature and front contact of relay 516, front contact and innermost right armature of relay 501', and winding of translating relay 311, individual to the selected outgoing link circuit, to grounded battery. Relay 311 energizes and closes a circuit for tens relay 315, extending from grounded battery, winding of said relay, back contact and innermost left armature of relay 310, back contact and innermost armature of relay 314, front contact and outer left armature of relay 311, back contact and right armature of relay 312, back contact and left armature of relay 313 to ground. Only four of the tens relays including relay 315 are shown, but it is to be understood that there are ten of these relays provided, nine of which are common to a group of relays individual to a number of subscriber's lines, some of said relays being illustrated within the dotted line enclosure in Fig. 3. It is to be understood that such relays as are shown in this dotted rectangle are individual to the connecting link circuit shown in Fig. 3. Relay 315 energizes in the circuit last described and through its left armature and front contact applies battery to the group of individual relays including relay 317. Relay 315 locks up over a circuit extending from grounded battery, winding, right armature and front contact of said relay, winding of relay 316, back contact and right armature of relay 318, right armature and front contact of relay 303 to ground. Relay 316 energizes and at its lower armatures breaks the incoming link circuit extending toward the called subscriber's substation. Ground is applied to the upper armature and front contact of relay 316 to prepare a

locking circuit for marginal relay 310 which, however, is not energized at this time.

Upon the release of relay 506, the locking ground at its left armature is removed from the counting relay 1 and the relay 507 which then restore, thus leaving all of the counting relays in normal position. Relays 509 and 510 remain energized over the previously described locking circuit for relay 509 and the entire impulse controlling mechanism is now ready to receive the second set of impulses corresponding to the units digit of the wanted line.

In response to the first impulse of the second set, relay 300 deenergizes and again closes the previously described energizing circuit for relays 504 and 505. Relay 506 again energizes and locks up to the ground at the back contact and left armature of relay 508. When relay 504 attracts its right armature, a circuit is closed for relay 515 extending from grounded battery, winding of relay 515, back contact and left armature of relay 517, front contact and left armature of relay 510, which remained energized, right armature and front contact of relay 504, front contact and lower armature of relay 503 to ground. Relay 515 energizes and locks up through the winding of relay 517, but this latter relay does not energize at this time, due to the shunt circuit extending from ground at the lower armature and front contact of relay 503, front contact and right armature of relay 504, left armature and front contact of relay 510, left armature and back contact of relay 517, right armature and front contact of relay 515, winding of relay 517, and back to ground at the lower armature of relay 503. Energization of relay 515 permanently opens, at its left armature, the circuit of relay 507, and thus prevents the same from becoming energized at the termination of the second set of impulses. The counting relays are again operated in accordance with the impulses transmitted in the same manner as previously described in connection with the tens impulses, and at the termination of this operation, the impulse circuit, through relays 504 and 505, is opened and these relays become deenergized. Release of relay 504 opens the shunt circuit for relay 517 which then energizes in the locking circuit for relay 515. Relay 508 is then energized over a circuit extending from grounded battery, winding of relay 508, right armature and front contact of relay 517 to ground. A circuit is then established for relay 516 extending from grounded battery, winding of relay 516, front contact and left armature of relay 508 to ground. Relay 506, after the expiration of an interval of time following the removal of ground at the back contact and left armature of re-

lay 508, becomes deenergized and opens the locking circuit for the counting relay which has remained energized, but before this occurs the relay individual to the called line is 5 energized. The energization of relay 516 over the circuit just described for the same extends the conductors 511 to 514 to the right armatures of junction relay 501'. Simultaneously with the energization of relay 10 516, a circuit is closed for marginal relay 310, extending from grounded battery, winding of relay 310, back contact and left armature of relay 308, outer left armature and front contact of relay 501, right armature and front contact of relay 508, front contact and left armature of relay 506 to ground, this circuit having been closed before relay 506 released. Relay 310 energizes in this circuit due to the fact the same 15 20 does not now pass through the resistance of relay 507 and in attracting its left armatures, said relay 310 extends the leads from the several translating relays 311 to 314 to the individual relays of the several groups. 25 Thus, by means of relay 310, the effect of energizing one or more of the translating relays is transferred from the tens relays to the individual relays which connect the incoming link circuit to the called line. Assuming now that the units digit of the 30 wanted line is 2, counting relay 2 would have been energized and locked up to ground at the front contact and left armature of relay 506, and previous to the deenergization of this latter relay, a circuit is closed from 35 ground at the left armature and front contact of counting relay 2, conductor 512, next to the uppermost armature and front contact of relay 516, front contact and next to the innermost armature of relay 501', and winding 40 of translating relay 312 to grounded battery. Relay 312 energizes and completes a circuit for individual relay 317 extending from grounded battery, left armature and front contact of relay 315, right winding of relay 317, front contact and next to the innermost left armature of relay 310 which has now become energized, back contact and 45 next to the innermost armature of relay 314, back contact and inner left armature of relay 311, front contact and left armature of relay 312, back contact and armature of relay 313 to ground.

At the time that relay 310 energizes, the 50 dial tone is disconnected and a locking circuit is closed for relay 310 extending from grounded battery, the winding, front contact and inner right armature of said relay, winding of relay 308, front contact and upper 55 armature of relay 316 to ground. Energization of relay 308 establishes an energizing circuit for relay 307 extending from grounded battery, winding of relay 307, front contact and right armature of relay 308 to ground. Relay 307 locks up over the circuit 60 65

extending from grounded battery, winding, front contact and inner armature of said relay, right armature and front contact of relay 303 to ground. Energization of relay 307 also breaks the circuit for relays 305, 70 501, 501' and 503 which circuit, as previously described, extended from grounded battery, outer right armature and back contact of relay 301 through the relays mentioned to ground at the lower armature of relay 503. 75 The relays which were energized and locked up in this circuit now release. Release of relay 503 breaks the locking circuit for relays 509, 510, 515 and 517. Release of the latter relay causes the deenergization of relay 508. Relays 504 and 506, having become deenergized, after a lapse of time, the entire impulse controlling mechanism is restored to normal, since the energizing circuit for any of the translating relays which had operated, is now broken, due to the release of relay 501'. It is now apparent that relays 315 317 are energized.

Let it be assumed now that the called line individual to relay 317 is idle and also, for 90 the sake of simplicity, that the line previously described as the calling line from substation A illustrated in Fig. 1, is the called line. It is then to be borne in mind that the called line junction relay 201 is deenergized. Now 95 upon energization of relay 317 individual to the called line, and shown in Fig. 2, a locking circuit is established therefor extending from grounded battery, left winding, front contact and innermost left armature of relay 100 317 to ground at the right armature and front contact of relay 303. A circuit is also closed from grounded battery at the cutoff relay 101 of the called substation, winding of said relay, innermost left armature and 105 back contact of relay 201, innermost left armature and back contact of junction relay 203, the innermost left armatures and back contacts of all other junction relays within the particular group with which the called 110 line is associated, right armature and front contact of relay 317, shown in Fig. 2, right winding of relay 318, right armature and front contact of relay 303 to ground. Relays 101 and 318 are energized in this circuit. 115 Energization of relay 318 breaks the previously described locking circuit for relay 315 which extended through the right armature and back contact of said relay 318. Relays 315 and 316 then deenergize and by 120 causing in turn the deenergization of relays 308 and 310 restore the junction line connecting relay selecting means to normal. Relay 318 also establishes a circuit for relay 306, extending from grounded battery, winding of relay 306, left armature, front contact and 125 left winding of relay 318, right armature and front contact of relay 303 to ground and relay 318 locks up in this circuit. Operation of relay 306 prevents the busy tone from be- 130

ing impressed upon the calling line. At the time that relay 316 deenergizes, a ringing current is applied to the called line extending from the ringing current generator, upper winding of relay 319, back contact and inner upper armature of relay 319, lower armature and back contact of relay 316, middle left armature and front contact of relay 317, the ringer apparatus at the called substation, front contact and outer left armature of relay 317, back contact and inner lower armature of relay 316, outer upper armature and back contact of relay 319 to ground. Relay 319 is marginal and the resistance of the ringer apparatus at the called substation prevents this relay from becoming energized at this time. However, when the called subscriber removes his receiver from its switch-hook, sufficient ringing current will pass through the upper winding of relay 319, to energize the same, and said relay, then locks up over a circuit extending from grounded battery, lower winding, lower armature and front contact of said relay, right armature and front contact of relay 306 to ground. Energization of relay 319 establishes a circuit for relay 309 extending from grounded battery, right winding of relay 309, front contact and inner upper armature of relay 319, then over the previously described circuit through the substation, uppermost armature and front contact of relay 319 and left winding of relay 309 to ground. Relay 309 supplies talking current to the called substation line and the connection now having been established, conversation between the calling and called subscribers may proceed.

At the termination of the conversation between the calling and the called subscribers, the replacing of the receiver upon its switch-hook at the calling subscriber's substation will release the relay 300 which in turn causes the deenergization of slow-to-release relay 303. The removal of ground from the right armature of relay 303 breaks the locking circuit for relay 307 which then releases. The circuit for relays 306 and 318, in which the latter relay is locked, is also broken by the removal of ground from the right armature of relay 303 and said relays 306 and 318 also deenergize. Release of relay 306 removes the holding ground for relay 319 which deenergizes and at its upper armatures breaks the circuit for relay 309 which also releases. The removal of ground at the right armature of relay 303 also causes the deenergization of the cut-off relays at the calling and called subscribers' substations and furthermore breaks the locking circuit for relay 317. In addition to causing the deenergization of the cut-off relay 101 at the calling subscriber's substation, the release of relay 303 also breaks the locking circuit for junction relay 201 and relay 302 which re-

lays were energized in the circuit for said cut-off relay.

If the wanted line had been busy as a calling line, one of the junction relays 201, 203 or similar relays individual to the several outgoing link circuits would be energized. However, upon energization of relay 310 at the termination of the selection of one of the counting relays corresponding to the units digit of the wanted line, relay 307 would be energized and at its outer armature break the circuit for relay 305, as previously described. It will be recalled that in the event the called line is idle, a circuit is established for the cut-off relay of said line which extended through the inner left armatures and back contacts of the junction relays 201 and 203, right armature and front contact of the individual relay 317, the right winding of relay 318 to ground at the right armature and front contact of relay 303. Therefore, when the wanted line is busy as a calling line, one of said junction relays being energized, the circuit just referred to through relay 318 which would otherwise have energized said relay is now broken and relay 318 will fail to operate. This will prevent energization of relay 306 so that upon the release of relay 305, a busy tone is applied to the calling line from the busy tone apparatus, back contact and outer armature of relay 305, back contact and inner left armature of relay 306 and right winding of relay 309 to ground battery. This busy tone current is induced into the left winding of relay 309 from whence the same is transmitted to the calling line. The calling subscriber hearing this busy tone replaces his receiver upon its switch-hook and causes the release of relay 300, with the result that all other relays which have been energized will now restore and the apparatus will be in condition to receive another call.

If the desired line is busy as a called line, relay 318 would again fail to energize due to a short-circuit extending from ground at the front contact and right armature of relay 303, shown in Fig. 3, through the right winding of relay 318, front contact and right armature of relay 317 individual to the called line, right armature and front contact of relay 317, also individual to the called line, and to an incoming link circuit which would have been employed in calling the wanted line, to ground at the right armature and front contact of the relay 303 of another switching apparatus such as that shown in Fig. 3 which would have been employed in selecting said wanted line. The failure of relay 318 to operate will again apply a busy tone to the calling line, as previously described, and as soon as the calling party replaces his receiver, the apparatus is restored to normal.

Should a calling subscriber at substation A, desire a connection to a central office exchange, the removal of the receiver at substation A will again cause the operation of 5 a calling line junction relay, such as the relay 201 and its outgoing link circuit, and also an impulse controlling mechanism such as shown in Fig. 5, in the same manner as previously described. The calling subscriber 10 may now dial for an idle central office trunk. Assuming that the digit corresponding to the central office trunk is 0, the counting relay 10 will be energized and locked up, in the same manner as described in connection 15 with the operation of the counting relays, thus applying ground to the three conductors 511, 512 and 514. As soon as relay 516 is energized, this ground is extended through the innermost, next to the innermost 20 and outermost armatures of relay 501', and through the windings of translating relays 311, 312 and 314 to grounded battery. These latter relays are energized and a circuit is then established for the relay 320 extending 25 from grounded battery, winding of relay 320, front contact and next to the outermost armature of relay 314, front contact and inner left armature of relay 311, front contact and right armature of relay 312, back contact and armature of relay 313 to ground. Relay 320 energizes and applies ground at its front contact and left armature to the conductor 321. Relay 320 locks up over the 30 circuit extending from grounded battery, winding, right armature and front contact of relay 320, winding of relay 316, back contact and right armature of relay 318, right armature and front contact of relay 303 to ground. Relay 316 is energized in this circuit. If all central office trunks are idle, the 35 ground at the left armature of relay 320 is extended over conductor 321 through the middle armature and back contact of the pre-selecting relay 204, individual to the first central office trunk, and right winding of junction relay 205 to grounded battery. Relay 205 is energized and establishes a circuit for the line relay 104 extending from 40 grounded battery, right winding of relay 104, back contact and inner lower armature of relay 105, front contact and next to the outermost left armature of relay 205, middle left armature and front contact of relay 201, subscriber's substation apparatus, front contact and outer left armature of relay 201, outermost left armature and front contact of relay 205, upper armature and back contact of relay 105 and left winding of relay 104 to ground. Relay 104 energizes and establishes 45 a circuit for slow-to-release relay 106 extending from grounded battery, winding of relay 106, front contact and innermost armature of relay 104 to ground. Energization of relay 106 establishes a locking

circuit for relay 205 extending from grounded battery, left winding, innermost left armature and front contact of relay 205 and left armature of relay 106 to ground. This locking circuit is established before the locking circuit for counting relay 10 is removed 65 by the deenergization of relay 506 since the release of this counting relay deenergizes translating relays 311, 312 and 314. Energization of relay 106 also establishes a circuit for the pre-selecting relay 204 extending 70 from grounded battery, winding of relay 204 to ground at the left armature of relay 106. Relay 204 energizes and thus pre-selects the next idle central office trunk so that another call directed to a central office trunk 75 coming in over a connecting circuit similar to that shown in Figure 3 will cause the actuation of relay 206, for instance, assuming that, as indicated, conductor 207 is associated with connecting circuit 208. At the 80 time relay 106 is energized, a circuit is also established for relay 301 extending from grounded battery, winding of said relay, next to the innermost left armature and front contact of relay 205 and left armature 85 of relay 106 to ground. Relay 301 energizes and at its outer right armature breaks the circuit for relay 305 with the same results as previously described, relay 503 deenergizing and permitting the return of the impulse 90 controlling mechanism to normal. Owing to the energization of relay 301, relays 300 and 303 also release. Deenergization of relay 303 removes the locking ground for relays 316 and 320 which then deenergize. 100 Relay 302 which was locked up to ground at the right armature of relay 303 does not, however, release since it now finds ground through the front contact and inner right armature of relay 301, next to the innermost 105 left armature and front contact of relay 205 and left armature of relay 106.

When relay 104 is energized, as previously described, a ground is applied through the middle and outermost armatures of relay 110 104 to both sides of the trunk leading to the central office. This will cause the operation of a signal at the central office operator's position in a manner well-known in the art, and upon the insertion of a plug 115 into the central office jack, a circuit is closed through the winding of relay 110. This relay energizes and closes the circuit for relay 111 traceable from grounded battery, winding of relay 111, right armature of relay 106, front contact and armature of relay 110, to ground. Energization of relay 111 places a shunt 125 about relay 110 for talking purposes and through its inner right hand armature establishes an energizing 120 circuit for relay 108 which in turn through its armature places a substitute ground on conductor 109 for guarding this trunk circuit. 125

- cuit. Energization of relay 111 closes a circuit for relay 105 traceable from grounded battery, winding of relay 105, outer right armature and front contact of relay 111.
- 5 Relay 105 energizes and extends the calling subscriber's line through to the central office operator's position and also breaks the circuit for line relay 104 which then deenergizes and in so doing removes the holding ground for relay 106. However, relay 106 does not deenergize since the holding ground therefor is now transferred to the lowermost armature and front contact of relay 105. The calling subscriber may now communicate with the operator at the central office exchange who then completes the connection between the calling and called subscribers in any well known manner. When the calling subscriber replaces his receiver upon its 20 switchhook at the termination of a call, a signal will be operated at the operator's position to indicate that the connection is to be dis-established. Removal of the plug from the central office jack causes the de-energization of relay 110 which, upon releasing, removes the holding ground for relay 111 which then releases and causes relay 105 and consequently relay 106 to deenergize. Release of relay 111 also removes the holding ground for relay 108 which releases. Deenergization of relay 106 removes the ground from its left armature and thereby causes the release of relays 204, 205, 301 and 302. The apparatus is now in normal 35 position.

On incoming calls from the central office, one of the receiving stations indicated at the left in Fig. 1 is first selected and upon ascertaining from the central office operator 40 the number of the desired subscriber within the exchange the attendant at the selected receiving station dials for the wanted subscriber in the same manner as described in connection with the establishment of a call 45 between subscribers within the exchange. The receiving stations are of the same type as the ordinary subscribers' stations with the exception that additional junction points are provided as shown. The connection between this additional apparatus and the ordinary equipment is indicated by the connection between the line of substation A and the first receiving station line. In establishing the call from the central office, the operator thereat, by inserting a plug into the jack associated with the trunk line, energizes relay 107. Relay 107, at its armature and contact closes a circuit for relay 108 which in turn, through its armature grounds conductor 109 to energize relay 204 so that an outgoing call to central office from the private branch exchange will not result in the seizure of the trunk now in use. Nothing else then happens until the operator applies ringing current to the trunk in the 50 ordinary manner. When she does this, relay 110 is energized by ringing current flowing through relay 110 and condenser 126. A circuit is then established for relay 112 extending from grounded battery, winding 70 of relay 112, contact spring 113, front contact and armature of relay 110 to ground. Relay 112 energizes and locks up over a circuit extending from grounded battery, winding, front contact and right armature of said 75 relay, and contact spring 114 to ground. Relay 112 at its left-hand armature then establishes a condition for the selection of one of the receiving stations shown at the left of Fig. 1. Should the first receiving station 80 be busy, a circuit may be traced from grounded battery, winding of junction relay 115, back contact and inner armature of relay 127, front contact and inner armature of pre-selecting relay 116, which is energized through the busy condition of the associated receiving station as will hereinafter appear, front contact and left armature of relay 112 to ground. Relay 115 locks up 85 over a circuit extending from grounded battery, winding, right armature and front contact of said relay, back contact and lower armature of relay 117, conductor 109, front contact and right armature of relay 108 to ground, and through its outermost lefthand 90 armature closes a circuit in parallel to relay 127 and cut off relay 101. Upon the operation of relay 115, a circuit is closed to apply ringing current to the receiving station apparatus extending from a source 95 of ringing current, left winding of relay 118, back contact and outer left armature of said relay, front contact and middle left armature of relay 115, the receiving station apparatus which is similar in all respects 100 to the apparatus of a subscriber's substation, innermost left armature and front contact of relay 115, inner left armature and back contact of relay 118 to ground. The ringing current is applied to the receiving station line until the attendant thereat removes the receiver from its switchhook at which time relay 118, energizes and locks up over a circuit extending from grounded battery, right winding, front contact and 105 right armature of relay 118, back contact and lower armature of relay 117, conductor 109, front contact and right armature of relay 108 to ground. Removal of the receiver from the switchhook at the receiving 110 station also closes a circuit traceable from grounded battery, winding of line relay 119, back contact and outer armature of cutoff relay 120, uppermost armature and back contact of relay 117, front contact and inner 115 left armature of relay 118, front contact and innermost left armature of relay 115, receiving station apparatus, middle left armature and front contact of relay 115, outer 120 left armature and front contact of relay 118, 125 outer left armature and front contact of relay 118, 130

winding of relay 121, back contact and inner upper armature of relay 117, inner armature and back contact of relay 120 to ground. Relays 121 and 119 energize in this circuit 5 and relay 121 establishes a circuit for slow-to-release relay 122 extending from grounded battery, winding of relay 122, front contact and armature of relay 121 to ground. Relay 122 now closes a circuit through its 10 right-hand armature and the impedance 128 across the trunk for energizing line relay 104. Relay 104 attracts its armatures and by closing a grounded shunt across the outgoing end of the trunk causes the energization 15 of relay 110 and extinguishes the usual supervisory lamp at the central office operator's position. At its innermost armature relay 104 energizes relay 106. Relay 106 at its left-hand armature breaks the 20 locking circuit for relay 112, which thereupon retracts its armatures. Energization of relays 106 and 110 closes a circuit previously described for relay 111. Relay 111 opens the circuit for relay 107 and at 25 its outermost right armature closes a circuit for relay 105. Relay 111 at its innermost right armature holds relay 108 energized. The energization of relay 105 cuts off relay 104 and extends the trunk to the 30 contacts of relay 117 whereby the party connected through the central office may communicate with the attendant at the receiving station through the condensers 129 and 130. Relay 119 in energizing attracts its 35 left armature and closes a circuit for relay 123 extending from grounded battery, winding of relay 123, front contact and left armature of relay 119 to ground. By attracting its right armature, relay 119 closes 40 a circuit to select the first idle outgoing link circuit in the same manner as described in connection with the establishment of a call between subscribers within the exchange. The attendant at the selected receiving station may now communicate with the central office operator and ascertain the 45 number of the wanted subscriber within the private branch exchange. Upon obtaining this information, the attendant may operate 50 the impulse sending device at the receiving station to transmit impulses corresponding to the digits of the wanted line, and thus operate the impulse controlling mechanism in the same manner as previously described. The impulses not interfering with the trunk line due to the condensers 129 and 130 and the slow-to-release construction of relay 122.

Should the wanted line be idle, ringing current will be applied to the line from relay 319 and upon the called subscriber answering, relay 309 will energize. A circuit will then be established which extends from grounded battery, upper winding of relay 117, outermost left armature and

front contact of relay 202 which became energized when line relay 119 operated, assuming that the first outgoing link circuit was the one selected, winding of relay 322, front contact and armature of relay 309 70 to ground. Relay 117 becomes energized in this circuit and by attracting its upper armatures extends the calling line over the central office trunk, through the armatures of relays 202, 319 and 317 individual to the called substation. Relay 117 locks up over the circuit extending from grounded battery, windings, front contact and lower armature of relay 117, front contact and right armature of relay 108 to ground. Relay 322 is also energized in the operating circuit of relay 117 and by attracting its armature closes a circuit for relay 301 extending from grounded battery, 80 winding of relay 301, armature and front contact of relay 322, front contact and armature of relay 309 to ground. Relay 301 energizes and releases the impulse controlling mechanism, as previously described, so that the same may again be selected. Relays 300 and 303 also become deenergized. Upon operation of relay 301, a holding ground for relay 302 is extended through the front contact and inner right armature of relay 301, armature and front contact of relay 322, and front contact and armature of relay 309. At the time that relay 117 became energized, the locking circuit for junction relay 115 which extended through the back contact and lower armature of relay 117 is broken and relay 115 releases. The pre-selecting relay 127 and the cutoff relay 101 also deenergize due to the release of relay 115. The locking circuit for relay 118 is also broken by the energization of relay 117 and said relay 118 together with relays 121 and 122 release. The attendant at the selected receiving station replaces the receiver upon its switchhook and said station can now be selected for another call. Conversation may now proceed between the calling subscriber and the called subscriber within the exchange and at the termination of a conversation, 115 the mechanism individual to the outgoing link circuit is returned to normal in the same manner as previously described. When relay 309 deenergizes, the holding ground is removed for relays 117, 322, and 301 which then deenergize. At the termination of a call, the operator at the central office receives the usual signal and removes the plug from its jack and in so doing releases relay 110, which removes the holding ground for relay 111. This relay deenergizes and removes the holding ground for slow-to-release relay 108. Relay 111 upon releasing breaks the circuit for cutoff relay 105. Relay 105 then releases and causes the 130

deenergization of relay 106 whereupon the mechanism is again in normal position, the testing ground for this mechanism having been removed upon deenergization of relays 5 108 and 106.

If the called line is busy, either as a calling or a called line, a busy tone from the apparatus BZ in Fig. 3 will be transmitted to the attendant at the selected receiving station in the same manner as described in connection with the establishment of a call between subscribers within the exchange, and said attendant upon hearing this busy tone, will inform the central office 10 operator of the fact that the wanted line is busy and will then replace the receiver upon the switchhook. The operator at the central exchange then gives this information to the calling subscriber and discontinues the connection. 20

What is claimed is:

1. In a telephone exchange system, calling and called subscribers' lines, another line for extending said calling line, an impulse controlling mechanism including a set of counting relays, means associated with said other line for selecting said impulse controlling mechanism, variably operable means for actuating said impulse controlling mechanism whereby certain of said counting relays are energized, and means directly responsive to the energization of said counting relays for extending said calling subscriber's line to the called subscriber's line. 30

2. In a telephone exchange system, calling and called subscribers' lines, an outgoing line for extending said calling line, an impulse controlling mechanism including a set of counting relays, means associated with 40 said outgoing line for selecting said impulse controlling mechanism, variably operable means for actuating said impulse controlling mechanism whereby certain of said counting relays are energized, intermediate lines to which are applied a certain electrical condition upon the energization of said counting relays, a switch individual to said called line, and means directly responsive to said electrical condition on said intermediate lines for operating said switch to connect the calling to the called line. 45

3. In a telephone exchange system, calling and called subscribers' lines, an outgoing line for extending said calling line, an impulse controlling mechanism including a set of counting relays, means associated with 55 said outgoing line for selecting said impulse controlling mechanism, variably operable means for actuating said impulse controlling mechanism whereby certain of said counting relays are energized, intermediate lines to which are applied a certain electrical condition upon the energization of said counting relays, a switch individual to said called 60

line, and a group of translating devices co-ordinating in response to the electrical condition on said intermediate lines for operating said switch to interconnect the calling and called subscribers' lines. 65

4. In a telephone exchange system, calling and called subscribers' lines, an outgoing line for extending said calling line, an impulse controlling mechanism including a set of counting relays, means associated with 70 said outgoing line for selecting said impulse controlling mechanism, variably operable means for actuating said impulse controlling mechanism whereby certain of said counting relays are energized, intermediate lines to which are applied a certain electrical condition upon the energization of said counting relays, a switch individual to said called line, and a plurality of relays certain of 75 which are directly responsive to said electrical condition for operating said switch to interconnect the calling and called subscribers' lines. 80

5. In a telephone exchange system, a plurality of subscribers' lines, outgoing and incoming lines serving said subscribers' lines, 90 a switch individual to each subscriber's line and operable to interconnect a calling with a called subscriber's line over outgoing and incoming lines, an impulse controlling mechanism to which an outgoing line is extended, 95 and a decimally controlled translating mechanism actuated by said impulse controlling mechanism for operating one of said switches in a non-decimal manner. 100

6. In a telephone exchange system, a plurality of subscribers' lines, outgoing and incoming lines serving said subscribers' lines, a switch individual to each subscriber's line and operable to interconnect a calling with a called subscriber's line over outgoing and incoming lines, said switches being arranged in groups, an impulse controlling mechanism to which an outgoing line is extended, intermediate lines associated with 105 said impulse controlling mechanism and upon which a certain electrical condition is imposed by said mechanism, translating devices responsive to said electrical condition, means operated by said translating devices in response to one operation of said impulse controlling mechanism for selecting a group of said switches, and means controlled by another operation of said impulse controlling mechanism for selecting a switch in the selected group. 115

7. In a telephone exchange system, a plurality of subscribers' lines, outgoing and incoming lines serving said subscribers' lines, a switch individual to each subscriber's line and operable to interconnect a calling with 120 a called subscriber's line over outgoing and incoming lines, said switches being arranged in groups, an impulse controlling mechanism 125

to which an outgoing line is extended, intermediate lines associated with said impulse controlling mechanism and upon which a certain electrical condition is imposed by said mechanism, translating devices responsive to said electrical condition, a group of relays one of which is operated by said translating devices in response to one operation of said impulse controlling mechanism for selecting a group of said switches, and a relay controlled by another operation of said impulse controlling mechanism to cause another actuation of said translating devices to select one of the switches in the selected group.

8. In a telephone exchange system, calling and called subscribers' lines, an outgoing line for extending said calling line, an impulse controlling mechanism including a set of counting relays, means associated with said outgoing line for selecting said impulse controlling mechanism, variably operable means for actuating said impulse controlling mechanism whereby certain of said counting relays are energized, means directly responsive to the energization of said counting relays for extending said calling subscriber's line to the called subscriber's line, and means actuated thereupon for restoring said impulse controlling mechanism to normal.

9. In a telephone exchange system, a plurality of subscribers' lines, outgoing and incoming lines serving said subscribers' lines, a switch individual to each subscriber's line and operable to interconnect a calling with a called subscriber's line over outgoing and incoming lines, said switches being arranged in groups, an impulse controlling mechanism to which an outgoing line is extended, intermediate lines associated with said impulse controlling mechanism and upon which a certain electrical condition is imposed by said mechanism, translating devices responsive to said electrical condition, means operated by said translating devices in response to one operation of said impulse controlling mechanism for selecting a group of said switches, means controlled by another operation of said impulse controlling mechanism for selecting a switch in the selected group, and means for restoring said impulse controlling mechanism to normal after each actuation thereof.

10. In a telephone exchange system, groups of subscribers' lines, outgoing and incoming lines serving said subscribers' lines, means for selecting an outgoing and an incoming line, impulse controlling mechanisms, switching means operable to select one of said impulse controlling mechanisms, a variably operable sending device for controlling the operation of the selected impulse controlling mechanism, groups of switches for interconnecting calling and called sub-

scribers' lines, each switch being individual to one of said lines, and a decimaly controlled translating mechanism directly responsive to said impulse controlling mechanism for selecting a group of switches and a switch in the selected group in a non-decimal manner.

11. In a telephone exchange system, groups of subscribers' lines, outgoing and incoming lines, means for automatically selecting an outgoing and an incoming line, an impulse controlling mechanism common to said outgoing lines and including counting relays, means actuated upon the selection of an outgoing line for thereupon selecting said impulse controlling mechanism, intermediate lines associated with said counting relays, means for operating said impulse controlling mechanism to energize certain of said counting relays whereby a certain electrical condition is imposed upon certain of said intermediate lines, a plurality of translating devices which coordinate in accordance with said electrical condition, and means responsive to the resultant coordination of said translating devices for extending the selected outgoing and incoming lines to one of said subscriber's lines.

12. In a telephone exchange system, groups of subscribers' lines, outgoing and incoming lines serving said subscribers' lines, means for automatically selecting an outgoing and an incoming line, an impulse controlling mechanism common to said outgoing lines and including counting relays, means actuated upon the selection of an outgoing line for thereupon selecting said impulse controlling mechanism, a variably operable impulse sending device for actuating one of said counting relays in response to each set of impulses transmitted, intermediate lines associated with said counting relays and upon certain of which are imposed an electrical condition by the actuation of said counting relays, a plurality of translating devices which coordinate in accordance with said electrical condition at the termination of the translation of each set of impulses, a group of switches selected by said translating devices in response to one set of impulses, and means for causing said translating devices to select a switch in said group at the termination of another set of impulses.

13. In a telephone exchange system, a plurality of subscribers' lines, outgoing lines common to said subscribers' lines, means for connecting one of said subscribers' lines to an outgoing line, a plurality of trunks, an impulse controlling mechanism to which said outgoing line is extended and including a set of counting relays, means directly responsive to the operation of one of said counting relays for extending said outgoing line to

said plurality of trunks, and means for pre-selecting an idle one of said trunks.

14. In a telephone exchange system, a plurality of subscribers' lines, attendants' lines, outgoing lines common to said subscribers' and attendants' lines, an operator's position, means for pre-selecting one of said attendants' lines, means for connecting the pre-selected attendant's line to an outgoing line, an impulse controlling mechanism to which said attendant's line is extended, means directly responsive to said impulse controlling mechanism for connecting said attendant's line to one of said subscribers' lines, and means operated thereupon for disconnecting said attendant's line and connecting the subscriber's line to said operator's position.

15. In a telephone exchange system, a plurality of subscribers' lines, attendants' lines, outgoing lines common to said subscribers' and attendants' lines, an operator's position, means for pre-selecting one of said attendants' lines, means for connecting the pre-selected attendant's line to an outgoing line, an impulse controlling mechanism to which said attendant's line is extended and including a set of counting relays, intermediate lines upon which a certain electrical condition is imposed when said counting relays are operated, means directly responsive to said electrical condition for connecting said attendant's line to one of said subscribers' lines, and means operated thereupon for disconnecting said attendant's line and connecting the subscriber's line to said operator's position.

16. In a telephone exchange system, a plurality of lines, a link circuit, groups of switches, a switch in each group being individual to one of said lines and operable to connect the same to said link circuit, means for operating said switches including two sets of conductors, each set being in the principal direction of a two co-ordinate system, a plurality of translating devices associated with said conductors, and means for controlling said devices to select a group of said switches through one set of conductors and a switch in the selected group through the other set of conductors.

17. In a telephone exchange system, a plurality of lines, a link circuit, groups of switches, a switch in each group being individual to one of said lines and operable to connect the same to said link circuit, means for operating said switches including two sets of conductors, each set being in the principal direction of a two co-ordinate system, a plurality of translating devices associated with said conductors, and subscriber controlled means for controlling said devices to select a group of said switches through one set of conductors and a switch

in the selected group through the other set 65 of conductors.

18. In a telephone exchange system, a plurality of lines, a link circuit, groups of switches, a switch in each group being individual to one of said lines and operable to 70 connect the same to said link circuit, means for operating said switches including two sets of conductors, each set being in the principal direction of a two co-ordinate system, a plurality of translating devices associated with said conductors, and a plurality of counting relays for controlling said devices to select a group of said switches through one set of conductors and a switch in the selected group through the other set 80 of conductors.

19. In a telephone system, subscribers' lines, permanently paired link circuits, subscriber controlled switching means comprising individually operable contacts for connecting said lines to said link circuits, and means for connecting said link circuits in pairs to form loop circuits whereby any line may be connected to any other line through a loop circuit. 90

20. In a telephone system, subscribers' lines, permanently paired link circuits, subscriber controlled switching means comprising individually operable contacts for connecting said lines to said link circuits, means responsive to the connection of a line to a link circuit to prevent the operation of other switching means for said link circuit to prevent double connections, and means for connecting said link circuits in pairs to 95 100 form loop circuits whereby any line may be connected to any other line through a loop circuit.

21. In a telephone system, calling and called subscribers' lines, permanently paired link circuits, subscriber controlled switching means comprising individually operable contacts for connecting said lines to said link circuits, means for connecting said link circuits in pairs to form loop circuits whereby any calling line may be connected to any called line through a loop circuit, and other switching means in the loop circuit which disconnects a calling line when applying ringing current to a called line to prevent 105 110 115 the application of said current to the calling line.

22. In a telephone system, subscribers' lines, permanently paired link circuits, means for joining said link circuits to form a loop circuit, whereby any line may be connected to any other line through said loop circuit, non-numerical switches through which said subscribers' lines are multiplied to said loop circuit, and numerical switches controlled from said subscribers' lines and through which said lines are also multiplied to said loop circuit. 120 125

23. In a telephone system, subscribers' lines, permanently paired link circuits, switching means comprising individually operable contacts for connecting each line to each link circuit, means for connecting said link circuits in pairs to form loop circuits whereby any line may be connected to any other line through a loop circuit, a

trunk circuit, and means controlled by said switching means and responsive to dialing impulses to extend a subscriber's line to said trunk circuit.

In witness whereof, I hereunto subscribe my name this 19th day of April, A. D. 1919.

SAMUEL B. WILLIAMS, JR.
